(57) **ABSTRACT**

A four-electrode fluorescent lamp having four filaments in a fluorescent lamp; each of the filament having two leads for being connected to a positive and a negative electrodes of a power source. A resistor is serially connected between a lead of one selective filament and a lead of another selective filaments. Each of the filaments is controlled by a transistor. A pair of capacitors are used to adjust the switching current of a pair of two transistors. The base of the transistor is connected to a respective diode set through a current limiting resistor. Each of the transistor is connected to a diode set. The four diodes are serially connected as a loop with two ends of the loop being connected to two ends of an AC power source. Thereby, a circuit for an alternative lighting four-electrode fluorescent lamp is formed.

FIG 2

**FOUR-ELECTRODE FLUORESCENT LAMP
AND THE CIRCUIT FOR ARRANGING THE
SAME**

FIELD OF THE INVENTION

The present invention relates to a four-electrode fluorescent lamp, and particularly to a circuit for an alternative lighting four-electrode fluorescent lamp.

BACKGROUND OF THE INVENTION

In the prior art designs, fluorescent lamps have two electrodes with each end of the lamp tube having one electrode and a simple circuit design. In actuation, the current consumed is large and vibration of illumination is great so that surge waves and noises generate to make uneasy feeling to uses. Moreover, in prior art design, an igniter is necessary. In starting process, flashing light generates go as to harm eyes of users.

Moreover, the cores of the lamps made of silicon steel or carbon iron powders as a hysteresis transformer which is heavy and generates magnetic fields and noises. Further, high frequency ignition is harmful to human, and particularly to hearing comprehension and brains. The medical instruments and aerospace surveillance systems will be interfered.

SUMMARY OF THE INVENTION

Accordingly, the primary object of the present invention is to provide a four-electrode fluorescent lamp having four filaments in a fluorescent lamp wherein each of the filament has two leads for being connected to a positive and a negative electrodes of a power source. A resistor is serially connected between a lead of one selective filament and a lead of another selective filament. Each of the filament is controlled by a transistor. A pair of capacitors are used to adjust the switching current of a pair of two transistors. The base of the transistor is connected to a respective diode set through a current limiting resistor. Each of the transistor is connected to a diode set. The four diodes are serially connected as a loop with two ends of the loop being connected to two ends of an AC power source. Thereby, a circuit for an alternative lighting four-electrode fluorescent lamp is formed.

The various objects and advantages of the present invention will be more readily understood from the following detailed description when read in conjunction with the appended drawing.

BRIEF DESCRIPTION OF THE DRAWINGS

FIG. 1 is a schematic view of the four-electrode fluorescent lamp of the present invention.

FIG. 2 shows the circuit arrangement of the four-electrode fluorescent lamp of the present invention.

**DETAILED DESCRIPTION OF THE
PREFERRED EMBODIMENTS**

Referring to FIG. 1, a first embodiment of the present invention is illustrated. A four-electrode fluorescent lamp FL is illustrated. There are four filaments A, B, C, and D in the four-electrode fluorescent lamp FL, each of the filament A, B, C, D is used as an electrode. The La1 and La2 are leads of the filament A. The La3 and La4 are leads of the filament B. The Lb1 and Lb2 are leads of the filament C. The Lb3 and

Lb4 are leads of the filament D. A resistor Rs is serially connected between the leads Lb2 and Lb3.

Referring to FIG. 2, another embodiment of the present invention is illustrated. The same elements of the four-electrode fluorescent lamp FL both in FIGS. 1 and 2 are numerated with the same numbers and thus the details will not be described herein. It is illustrated that the four electrode fluorescent lamp FL of the present invention is arranged in the electronic circuit. One lead of each of the two electrodes A, and D is connected to a collector of a respective PNP transistor TR-1 and TR-4 and one lead of each of the two electrodes B, and C is connected to a collector of a respective NPN transistor TR-2 and TR-3. The transistors TR-1, TR-2, TR-3 and TR-4 are used as switches for turning on or off the respective leads.

The capacitors C1, C2, C3 and C4 serve to store charges and charge the respective transistors so as to actuate the respective transistors. The capacitor C1 is connected between the emitters of the transistors TR-1 and TR-2, and the capacitor C2 is connected between the collectors of the transistors TR-1 and TR-2. The capacitor C4 is connected between the emitters of the transistors TR-3 and TR-4, and the capacitor C3 is connected between the collectors of the transistors TR-3 and TR-4. The base of transistor TR-1 is connected to the emitter of the transistor TR-2. The base of transistor TR-2 is connected to the emitter of the transistor TR-1. The base of transistor TR-3 is connected to the emitter of the transistor TR-4. The base of transistor TR-4 is connected to the emitter of the transistor TR-3.

All the diode sets are serially connected as a diode loop, And one end of the loop is connected to an C' end of the power source and another end of the loop is connected to an A' end of the power source.

Each of the transistors TR-1, TR-2, TR-3 and TR-4 is connected to a diode set through current limiting resistors; for example, the transistor TR-1 is connected to diodes D1 and D2 through the resistor R1-R3. The transistor TR-2 is connected to diodes D3 and D4 through the resistor R4-R6. The transistor TR-3 is connected to diodes D5 and D6 through the resistor R7-R9. The transistor TR-4 is connected to diodes D7 and D8 through the resistor R10-R12.

The fuse FUSE serves to as a safety protection of the circuit.

The operation of FIG. 2 will be described here. When the power switch S-1 is in the off point, the power turns off and the four-electrode fluorescent lamp FL turns off.

When the switch S-1 is at H point, the four-electrode fluorescent lamp FL is at high illumination. When the switch S-1 is at MR point, the four-electrode fluorescent lamp FL is at middle illumination. When the switch S-1 is at LR point, the four-electrode fluorescent lamp FL is at low illumination.

For the PNP transistor TR-1, the positive half cycle of the A' end of the AC voltage will conduct the diodes D1 and D2. Since the resistor R1 is smaller than resistor R2, the transistor TR-1 cuts off and thus the electrode A will not conduct. The diodes D1 and D2 cause that the capacitor C1 is charged. When the voltage of C' end of the AC power source enters into the negative half cycle, the diodes D1 and D2 cut off and the charges in the negative side of the capacitor C1 causes that the transistor TR-1 conducts so that the charges at the positive side of the capacitor C1 flows through transistor TR-1 to charge the capacitor C2 and the lead La1.

For the NPN transistor TR-2, the negative half cycle of the C' end of the AC voltage will conduct the diodes D4 and D3.

Since the resistor R₆ is smaller than resistor R₅, the transistor TR-2 cuts off and thus the electrode C will not conduct. The diodes D₄ and D₃ cause that the capacitor C₁ is charged. When the voltage of the C' end in the AC power supply end enters into the positive half cycle, the diodes D₄ and D₃ cut off and the charges in the positive side of the capacitor C₁ causes that the transistor TR-2 conducts so that the charges at the positive side of the capacitor C₁ flows through transistor TR-1 to charge the capacitor C₂ and the lead Lb₁.

For the NPN transistor TR-3, the negative half cycle of the A' end of the AC voltage will conduct the diodes D₅ and D₆. Since the resistor R₇ is smaller than resistor R₈, the transistor TR-3 cuts off and the electrode B will not conduct. The diodes D₅ and D₆, cause that the capacitor C₄ is charged. When the voltage of the C' end in the AC power supply end enters into the positive half cycle, the diodes D₅ and D₆ cut off and the charges in the negative side of the capacitor C₄ causes that the transistor TR-3 conducts so that the charges at the positive side of the capacitor C₃ flows through transistor TR-3 to charge the capacitor C₃ and the lead La₄.

For the NPN transistor TR-4, the positive half cycle of the C' end of the AC voltage will conduct the diodes D₈ and D₇. Since the resistor R₁₂ is smaller than resistor R₁₁, the transistor TR-4 cuts off and thus the electrode D will not conduct. The diodes D₈ and D₇ cause that the capacitor C₄ is charged; When the voltage of the C' end in the AC power supply end enters into the positive half cycle, the diodes D₈ and D₇ cut off and the charges in the positive side of the capacitor C₄ causes that the transistor TR-4 conducts so that the charges at the positive side of the capacitor C₄ flows through transistor TR-4 to charge the capacitor C₃ and the lead Lb₄. When capacitor C₁ is charged, the transistors TR-1 and TR-2 cut off. When the capacitor C₄ is charged, transistors TR-3 and TR-4 cut off. When transistors TR-1 and TR-2 conducts, the capacitor C₂ is charged. When transistors TR-3 and TR-4, the capacitor C₃ is charged. When the capacitors C₂ and C₃ are charged, the positive charges of capacitor C₂ is guided to the lead La₁ and negative charges of the capacitor C₂ is guided to the lead Lb₁. The negative charges of the capacitor C₃ is guided to the lead La₄ and positive charges thereof is guided to the lead Lb₄. Current froth lead Lb₄ flows to the lead Lb₃ through the filament D. Then the current flows through the resistor R_s, then flow through the filament C to lead Lb₁ to the negative polarity of capacitor C₂. Thereby, a serial loop is formed. Thereby, the voltage difference between the filament A and filament B is $2V_0C$. Then electrodes A and B are discharged so as to generate heat (so called cool cathode method) so that the mercury in the lamp will flow greatly. Since the circuit is a serial connected circuit, the temperature of electrodes C and D will increase (so call hot cathode method) so that a great amount of electrons generate. Thereby, the illumination of the lamp is increased and the impedance in the tube is decreased so that the current is increased. Moreover, since the AC power supplies to the circuit by a sequence of C₁, C₂, C₄ and C₃. Thereby, the voltages of La₁ and Lb₁ and voltages of La₄ and Lb₄ are alternatively changed so that the lamp tube lights up.

Advantages of the present invention will be described hereinafter.

The power of the four-electrode fluorescent lamp is determined by the capacitances of the capacitors.

The Q value is equal to C (capacitance) * V (voltage) which is equal to I (current) * T (time). No igniter, steady hysteresis transformer, and high frequency is required.

The hot and cold cathodes are used to control the time sequence of the power source.

The resistor R_s has a function of adjusting the igniting actuating current so as to protect the electrodes.

The currents are alternatively changed so that the emitting light is softly and warmly.

The capacitance of the capacitor C₂ has a value of 0.003 μ F and capacitance of the capacitor C₃ has a value of 0.003 μ F which serves as a surge and noise absorber.

10 The present invention will not be interfered by EM waves or fields.

The material used is simple. Power can be saved.

15 The present invention is thus described, it will be obvious that the same may be varied in many ways. Such variations are not to be regarded as a departure from the spirit and scope of the present invention, and all such modifications as would be obvious to one skilled in the art are intended to be included within the scope of the following claims.

20 What is claimed is:

1. A four-electrode fluorescent lamp having four filaments in a fluorescent lamp; each of the filament having two leads for being connected to a positive and a negative electrodes of a power source; a resistor being serially connected between a lead of one selective filament and a lead of another selective filament.

2. A circuit for an alternative lighting four-electrode fluorescent lamp comprising a four-electrode fluorescent lamp FL; the four-electrode fluorescent lamp FL containing four filaments A, B, C, and D as electrodes; the filament A having leads La₁ and La₂; the filament B having leads La₃ and La₄; the filament Q having leads Lb₁ and Lb₂; and the filament D having leads Lb₃ and Lb₄; and a resistor R_s being serially connected between the leads Lb₂ and Lb₃; the circuit comprising:

four transistors TR-1, TR-2 TR-3 and TR-4; wherein one lead of each of the two adjacent electrodes A, and D is connected to a collector of a respective PNP transistor TR-1 and TR-4 and one lead of each of the two electrodes B, and C are connected to a collector of a respective one of two NPN transistors TR-2 and TR-3; the transistors TR-1, TR-2, TR-3 and TR-4 are used as switches for turning on or off the respective leads; a base of the transistor TR-1 is connected to an emitter of the transistor TR-2; a base of transistor TR-2 is connected to an emitter of the transistor TR-1; a base of the transistor TR-3 is connected to an emitter of the transistor TR-4; a base of the transistor TR-4 is connected to an emitter of the transistor TR-3;

50 four capacitors C₁, C₂, C₃ and C₄ for storing charges and charging the respective transistors TR-1, TR-2, TR-3 and TR-4 so as to actuate the respective transistors TR-1, TR-2, TR-3 and TR-4; wherein the capacitor C₁ is connected between the emitters of the transistors TR-1 and TR-2, and the capacitor C₂ is connected between the collectors of the transistors TR-1 and TR-2; the capacitor C₄ is connected between the emitters of the transistors TR-3 and TR-4, and the capacitor C₃ is connected between the collectors of the transistors TR-3 and TR-4;

55 four diode sets; each containing two diodes; the four diode sets being serially connected as a diode loop, and one end of the loop being connected to a C' end of a power source and another end of the loop being connected to A' end of the power source; wherein each of the transistors TR-1, TR-2, TR-3 and TR-4 being connected to a respective diode set through a respective

current limiting resistor; namely the transistor TR-1 is connected to diodes D1 and D2 through resistors R1 and R3; the transistor TR-2 is connected to diodes D3 and D4 through resistors R4 and R6; the transistor TR-3 is connected to diodes D5 and D6 through resistor R7 and R9; and the transistor TR-4 being connected to diodes D7 and D8 through resistors R10 and R12.

3. The circuit for an alternative lighting four-electrode fluorescent lamp as claimed in claim 2, wherein a capacitance of each capacitor is adjustable for determining supply currents to the transistors. 10

4. The circuit for an alternative lighting four-electrode fluorescent lamp as claimed in claim 2, wherein cool cathode way and hot cathode way are used in an actuation of the four-electrode fluorescent lamp.

5. The circuit for an alternative lighting four-electrode fluorescent lamp as claimed in claim 2, wherein capacitance of the capacitor C2 has a value of $0.003 \mu\text{F}$ and capacitance of the capacitor C3 has a value of $0.003 \mu\text{F}$ which serve surge and noise absorbers.
